UNITED STATES PATENT OFFICE.

JOHN H. WHITING, OF PUNXSUTAWNEY, PENNSYLVANIA, ASSIGNOR TO INTERNATIONAL MOTOR CO., OF PUNXSUTAWNEY, PENNSYLVANIA.

HEADLIGHT FOR LOCOMOTIVES.

1,156,262.

Specification of Letters Patent.

Patented Oct. 12, 1915.

Application filed April 29, 1915. Serial No. 24,705.

To all whom it may concern:

Be it known that I, JOHN H. WHITING, citizen of the United States, residing at Punxsutawney, in the county of Jefferson 5 and State of Pennsylvania, have invented certain new and useful Improvements in Headlights for Locomotives, of which the following is a specification.

This invention relates to head lights, and 10 more particularly to improved means for insuring the projection of the rays of light upon the road-bed regardless of the curvature of the track.

The invention comprises novel means for 15 automatically turning the head-light by means of the side elevation of the locomotive or car as in rounding curves, the construction being such that the head-light's rays are directed along the road-bed at all 20 times.

The invention consists of the combination with a rotatable head-light, of a pendulum suitably connected to the head-light.

The invention also includes a governor device 25 associated with the pendulum to guard against unsteadiness or shock due to constant vibration.

The construction of the improvement will 30 be fully described hereinafter in connection with the accompanying drawings which form a part of this specification, and its features of novelty will be defined in the appended claims.

In the drawings: Figure 1 is a side elevation 35 of a head-light embodying the invention, Fig. 2 is a perspective view of the same, and Fig. 3 is a detail sectional view of the hollow pivotal mounting of the head-light.

The reference numeral 1 designates a support 40 formed with an opening to receive a journal and the depending pivotal stem 2 of the head-light 3, the latter being readily rotatable, and being supported upon co-acting disks 4 and 5, between which anti-friction balls 6 are arranged to render the turning movement of the head-light as sensitive as possible. Secured below the support 1 is an angle bracket 7 provided with a bearing

8 upon which is journaled a pendulum rod 50 9 to which is attached a weight 10.

The stem 2 of the head-light is connected by an arm 11 with the upper end of the pendulum rod, and through this connection the head-light is turned by the swinging of 55 the pendulum.

As a means of guarding against shocks, and maintaining a steady light I employ a rod 12 loosely mounted upon, and near the upper end of the pendulum rod 9 and also 60 loosely journaled into the bracket 7 and carrying an adjustable weight 13. This counterweight prevents shocks and uneven movements which might otherwise be caused by sudden movements of the pendulum. 65

As shown in Fig. 3 the pivotal mounting of the head-light is hollow for accommodating the wires 14 in case electric lights are used with the head-light.

Having fully described my invention what 70 I claim, and desire to secure by Letters Patent is:—

1. The combination with a support having an opening, a head-light having a pivotal support extending through said opening, an 75 angle bracket depending from said support, a pendulum supported by said bracket, a connection between the pendulum and the pivotal head-light support, and means for preventing shocks due to the sudden movements of the pendulum. 80

2. The combination with a support formed with an opening, of a rotatable head-light having a depending central pivot, an angle bracket secured to said support, and provided with a bearing, a pendulum journaled upon said bearing, an arm connecting said pendulum and the pivotal support of the head-light, a horizontally disposed rod supported upon said vertical pendulum rod and 85 guided by said bracket, and a weight supported on said rod. 90

3. The combination with a support formed with an opening, of a rotatable head-light provided with a hollow pivotal support extending through said opening, co-acting ball bearing disks between the head-light and support, an angle bracket secured to said 95

support and provided with a bearing, a weighted pendulum journaled upon said bearing, an arm connecting said pendulum and pivotal support, a horizontal rod loosely journaled in said bracket and a weight on said rod.

In testimony whereof I affix my signature in the presence of two witnesses.

JOHN H. WHITING.
